[57] CLAIM

The ornamental design for a suture dispenser, as shown and described.

DESCRIPTION

FIG. 1 is an isometric view of a suture dispenser showing my new design;

FIG. 2 is a left side elevational view thereof shown on a slightly larger scale than FIG. 1, the right side elevational view being a mirror image thereof;

FIG. 3 is a front elevational view thereof shown on about the same scale as FIG. 2;

FIG. 4 is a rear elevational view thereof shown on about the same scale as FIG. 2;

FIG. 5 is a top plan view thereof shown on about the same scale as FIG. 2;

FIG. 6 is a bottom plan view thereof shown on about the same scale as FIG. 2;

FIG. 7 is an isometric view of a second embodiment of FIG. 1, shown on about the same scale as FIG. 1;

FIG. 8 is a left-side elevational view of the embodiment shown in FIG. 7, shown on a slightly larger scale than FIG. 7, the right-side elevational view being a mirror image thereof;

FIG. 9 is a front elevational view of the embodiment shown in FIG. 7, shown on about the same scale as FIG. 8;

FIG. 10 is a rear elevational view of the embodiment shown in FIG. 7, shown on about the same scale as FIG. 8;

FIG. 11 is a top plan view of the embodiment shown in FIG. 7, shown on about the same scale as FIG. 8; and,

FIG. 12 is a bottom plan view of the embodiment shown in FIG. 7, shown on about the same scale as FIG. 8.
